Primary Examiner — Karen E. Eldridge Powers*Assistant Examiner* — Jasmine Mlinarcik(74) *Attorney, Agent, or Firm* — Wilson Sonsini Goodrich & Rosati(57) **CLAIM**

The ornamental design for a sun hat with a rectangular-shaped electronic display, as shown.

DESCRIPTION

FIG. 1 shows a perspective view of a sun hat with a rectangular-shaped electronic display;

FIG. 2 shows a front elevation view of the sun hat with a rectangular-shaped electronic display;

FIG. 3 shows a side elevation view of the sun hat with a rectangular-shaped electronic display; and,

FIG. 4 shows a top plan view of the sun hat with a rectangular-shaped electronic display.

The partial human figure depicted by broken lines illustrates how the claimed design may appear when worn and forms no part of the claimed design.
